UNITED STATES PATENT OFFICE

ALLAN S. BARROWS, OF LOS ANGELES, CALIFORNIA, ASSIGNOR TO THE YOUNGSTOWN STEEL DOOR CO., OF CLEVELAND, OHIO, A CORPORATION OF OHIO

SLIDING-DOOR OPERATOR

Original application filed June 27, 1924, Serial No. 722,761. Divided and this application filed June 18, 1928. Serial No. 286,372.

This invention relates to improvements in sliding door operator, and more particularly sliding door operators adapted for house cars, and this application is a division of my pending application, Serial No. 722,761, for Improvement in doors, filed June 27, 1924.

One object of this invention is to provide simple and effective operating mechanisms for slidable doors, and more especially slid- 10 able doors of the outside type for box cars and automobile cars, wherein a powerful initial opening movement and a powerful final closing movement may be imparted to the doors.

More specifically, an object of my invention is to provide a door operating mechanism for the purpose indicated, which comprises an operating lever of the second class and a cooperable detachable link so arranged that the lever and link may be disconnected after the initial opening movement has been imparted to the door.

Other objects of the invention will more clearly appear from the description and claims hereinafter following.

In the drawing, forming a part of this specification, Figure 1 is a broken side elevational view of a portion of a box car, showing my improvements in connection therewith. And Figure 2 is a broken horizontal sectional view, upon an enlarged scale, corresponding to the line 2-2 of Figure 1.

In said drawing, the side wall of the car is indicated at 10, the same having a single door opening 11 provided therein, said door opening being defined, in part, by vertical wood posts 12 and 13 which are preferably sheathed to protect the same by metal plates 14-14.

My improvements have been illustrated in connection with a slidable door of the all-metal type, said door being indicated generally by the reference character A and, as shown, comprises three sheet metal panels 15, 16 and 17, each of the panels having a central, flat, dished portion and provided around the margins thereof with an outwardly extending, inclined section 18 and a flat flange 19. The flat flanges 19 on the meeting adja- 50 cent edges of the panels are overlapped and

riveted, as indicated at 20-20, thereby providing what may be termed two horizontally extending corrugations within the area of the door. Around the other edge portions of the panels suitable rolled sections are preferably secured thereto, a Z-bar 21 being used along the front edge of the door, as best indicated in Figure 2, and an angle 22 along the vertical rear edge. 55

Bridging strips 23-23 are also preferably employed, each strip being riveted to the main portions of the panel sheets inwardly of the offset sections and to the rolled edge elements, as will be understood. With the front edge construction shown, a double-ply, 60 flat, marginal portion is provided, as indicated at 24, the same being adapted to enter a suitable recess provided between the front post 12 and the outer flange 25 of a Z-bar front stop 26. The rear edge angle 22 is 70 preferably provided with a forwardly turned flange 27 at its inner end, the same being adapted to be seated behind a flange of an angle weather-sealing strip 28. As will be understood, my improved door operator is 75 not limited to any particular type of door, the one shown and described being for purposes of illustration only.

My improved door operator comprises, broadly, an operating lever B, mounted on a bracket C, and a link D mounted on a bracket E attached to the door A. 80

The bracket C may be of any suitable form adapting it for attachment to the specific construction of the car side member or other member to which it is applied. In the instance shown, said bracket C is of more or less right angular form, having a flange section 29 riveted to the web of the door stop 26, and a flange section 30 spaced outwardly from the door stop and approximately in a plane coinciding with a plane passing through the crest of the offset portions of the door. The bracket C is suitably reinforced by ribs 31, and the section 30 is provided with an outstanding pivot stud or boss 32, on which is pivotally mounted the lever B, the latter being held in place by any suitable means, such as the washer 33 and rivet 95 100

34, the latter passing through the washer 33 and stud 32, as will be understood.

The operating lever B is pivotally mounted at its upper end on the stud 32, as above described, and is provided at its lower end with a hand-hold or grip section 35. Intermediate its ends, the lever B is provided with a preferably integral stud 36 extended outwardly from the car side, said stud having a slightly enlarged annular flange 37 at its outer end, for the purpose hereinafter described.

The link attaching bracket E will be of any suitable desired formation adapting it to the particular configuration of door to which applied. In the instance shown, the bracket E has a bottom flange 38 riveted to the flat dished portion of the lower panel 17; an outwardly inclined section 39 fitting against the inclined section 18 of the panel sheet; and an outer main hub section 40, the latter being provided with a stud 41 on which is loosely pivotally mounted the link D. The stud 41 is preferably of greater length than the width of the link D so that the latter may not only swing on the stud 41 in a plane parallel to the plane of the door, but may also be swung laterally with respect to the door, for the purpose hereinafter described.

20 The link D is preferably held in assembled relation with the bracket E by any suitable means, such as the washer 42 and rivet 43.

The link D, at its free end, is provided with an opening 44 just large enough to pass over the flanged end 37 of the stud 36, so that it may be received on the stud proper 36, and when in operative position will be partially overlapped by the flange 37 so as to prevent accidental disengagement, laterally, of the link.

46 In the drawing, the operative interconnected condition of the lever B and link D is shown in full lines, with the parts in such position as to start the opening movement of the door. This is accomplished by the operator swinging the lever B in a counter-clockwise direction, it being observed that the power from the lever B is applied to the link D substantially in a horizontal line passing through the pivotal connection of the link D with the door, thus obtaining the most efficient application of the power to the door and minimizing any tendency to cock or tilt the door while starting it. When the door has been shifted in an opening direction as far as desired and within the range of the door operator, the link D then has its free end disengaged from the stud 36, the balance of the opening movement of the door being accomplished in any other suitable manner. When the link and lever are disengaged, it is obvious that each will hang in a dependent position, as shown by the dotted lines in Figure 60 1. The reverse procedure will be gone

through in effecting the final closing movements of the door, as will be obvious.

As will be appreciated from the preceding description, the door operator consists of a minimum number of parts and so arranged as to most effectively apply the power to the door in either an opening or closing direction. Although I have illustrated the operator with the lever supported from a fixed part of the car and the link attached to the movable door, it is obvious that the arrangement of these parts may be reversed, and further that the door operator may be made effective between the usual main and auxiliary doors of an automobile car, without departing from the spirit of the invention.

While I have herein shown and described what I consider the preferred manner of carrying out my invention, the same is merely illustrative and I contemplate all changes and modifications that come within the scope of the claim appended hereto.

I claim:

In a door operating mechanism, the combination with a horizontally slideable door member; of a second member toward and from which the door member is movable; an operating lever pivoted at its upper end to one of said members; a link pivotally attached at one of its ends to the other of said members so as to swing in a vertical plane; and cooperable, detachable, interengaging means on the free end of said link and on said lever, the means on said lever being disposed at a point intermediate the pivoted and free ends of the lever and so located that, when the door is in closed position and the link and lever are interengaged, the link is disposed substantially horizontally and the actuating force transmitted from the lever to the link in a direction to open the door, initially passes substantially horizontally lengthwise of the link.

In witness that I claim the foregoing I have hereunto subscribed my name this 11th day of June, 1928.

ALLAN S. BARROWS.
